US00D931798S

(12) **United States Design Patent** (10) **Patent No.:** **US D931,798 S**
(45) **Date of Patent:** **** Sep. 28, 2021**

(54) **BATTERY**

(71) Applicant: **SHENZHEN SEABOOM CO., LTD,**
Guangdong (CN)

(72) Inventor: **Xiaoshan He**, Guangdong (CN)

(73) Assignee: **SHENZHEN SEABOOM CO., LTD,**
Shenzhen (CN)

(**) Term: **15 Years**

(21) Appl. No.: **29/717,952**

(22) Filed: **Dec. 19, 2019**

(51) **LOC (13) Cl.** **13-02**

(52) **U.S. Cl.**

USPC **D13/103**

(57) **CLAIM**

The ornamental design for a battery, as shown and described.

DESCRIPTION

FIG. 1 is a perspective view of a battery showing my new design;

FIG. 2 is another perspective view thereof;

FIG. 3 is a front elevation view thereof;

FIG. 4 is a left side view thereof;

FIG. 5 is a top plan view thereof; and,

FIG. 6 is a bottom plan view thereof.

The right side view is the same as the left side view and it is left out;

The back elevation view is the same as the front elevation view and it is left out.

1 Claim, 6 Drawing Sheets
